RECORDING AND REPRODUCING HEAD

Bernard F. McNamee, Westwood, Calif., assignor
to United Acoustigraph Corporation, Los
Angeles, Calif., a corporation of Nevada

Application June 19, 1939, Serial No. 279,847

5 Claims. (CL 179—100.41)

This invention relates to a head that may be utilized in connection with recording and reproduction of sound, such for example, as for phonograph records, dictating machines, or the like.

Heads of this character usually utilize a movable bar or armature of magnetic material, arranged between closely spaced opposing poles of a magnet. This armature is usually mounted for oscillation about an axis transverse to the armature. The armature carries a stylus that is intended to be in contact with the record or the record blank. For recording purposes, the armature is influenced by an electromagnetic coil disposed around the armature, and which is fed with currents corresponding to the sound impulses to be recorded. The magnetic reaction between the armature and the magnet poles causes the stylus to oscillate in accordance with the impulses to be recorded. The oscillations are recorded on a film or blank by pressure or by cutting or engraving.

When the head is used for playback or reproduction, the stylus is mechanically moved in accordance with the record grooves; and such movements are caused to induce varying currents in the electromagnetic coil. The current impulses may then be appropriately amplified and utilized to operate a translating device such as a sound reproducer or secondary recorder.

It may seem that the head, appropriately designed for sound reproduction, would be immediately useful for recording. Actually, different requirements are imposed, so that very often the recording and playback functions are attained by the aid of separate devices.

Thus, in recording whether by embossing or cutting a record blank, the stylus is called upon to perform an appreciable amount of work, and the stylus bar which oscillates about an axis in the head accordingly is called upon to transmit force from the pole piece at its inner end to the stylus at its outer end. Under these conditions, it is desirable to prevent any movement or looseness of the stylus bar relative to its axial support, since such movement reduces the amplitude of movement of the stylus point as well as introducing distortion. It has been common to provide jewelled or other hard material pivots to form such axial support, but these require careful adjustment which is difficult to maintain, since if the points are not set sufficiently tight looseness is present, and if they are too tight undesired damping results. In reproducing heads, the stylus bar is called upon to transmit rela-

tively much less force and it has been common to support the stylus bars of such heads in rubber bushings. These are inexpensive, require no adjustment and are free of any looseness or rattle. 5 When heads having stylus bars supported in this manner are used for recording, however, it has been found that the resilient bushing is compressed allowing the axis of the stylus bar to move with the undesirable results just mentioned. It is accordingly a principal object of this invention to provide an improved type of support for the stylus bar in such heads.

It is another object of this invention to provide a head that is adapted to perform well for both 10 recording and reproduction.

It is another object of this invention to provide an improved form of head of this general character.

This invention possesses many other advantages, and has other objects which may be made 20 more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of this invention is best 25 defined by the appended claims.

Referring to the drawing:

Figure 1 is an enlarged sectional view of a head embodying the invention;

Fig. 2 is a plan view, partly in section, of the device shown in Fig. 1;

Fig. 3 is a sectional view taken along plane 3—3 of Fig. 1;

Fig. 4 is a fragmentary view similar to Fig. 2 and illustrating the manner in which certain 40 adjustments may be made;

Fig. 5 is a front elevational view, partly broken away, of the device shown in Fig. 1; and

Fig. 6 is a fragmentary sectional view taken along plane 6—6 of Fig. 4.

The reproduction and recording of impulses, such as sound impulses may be accomplished by the aid of the present apparatus. For this purpose use is made of a stylus 8, which is adapted to cooperate mechanically with a record or a record blank. In order to adapt this stylus both for reproduction as well as for recording, it may be appropriately formed with a suitable hard point capable of permanently deforming a record blank without cutting it, and capable as well of 45 following a record groove without injury to the

record. For this purpose the stylus 8 may be appropriately formed with some gem point, such as a sapphire point.

In the present instance, as is quite common, the stylus is arranged to be supported on a magnetically influenced oscillatory armature structure, made from appropriate magnetic material. This armature structure includes a tubular socket member 9, having a lower saddle extension 10 for guiding the insertion of the stylus 8 into the socket 9. The socket 9 is shown as formed integral with a flattened end member or pole 11, which is intended to cooperate with magnetic forces in a manner to be hereinafter described.

The armature structure is intended to be oscillatable about an axis transverse to the socket 9. For this purpose there are integrally formed oppositely directed extensions 12 and 13 which cooperate to form a bearing structure for the armature structure 9-11. Furthermore, in order to secure the stylus 8 in place, the upper extension 13 may be threaded for the reception of a thumb clamping screw 14.

The bearing support for the armature structure is shown to best advantage in Figs. 1, 2 and 5. Thus the extensions 12 and 13 are respectively encompassed by the resilient sleeves 15 and 16. These sleeves may be of rubber or the like which resiliently resists any force tending to move the armature structure to an eccentric position with respect to the sleeves 15 and 16.

The sleeves 15 and 16 are adapted to be clamped between two clamping elements. One clamping element includes the inwardly turned ends 17 and 18 of a pair of supports, the structure of which will be hereinafter detailed. The adjacent edges of the inwardly turned ends 17 and 18 form a wedge-shaped space contacting with the sleeves 15 and 16. They are firmly held in the space by the aid of a clamping cap 19, which is apertured at its center for the free passage of the socket 9, outwardly from the cap 19.

The inwardly turned ends 17 and 18 are shown in this instance as formed integrally with the side supporting plates 20 and 21. These supporting plates are arranged to provide a support for a magnet structure, such as the permanent horseshoe magnet 1. This horseshoe magnet is shown as provided with the downwardly directed end faces 2 and 3, which are coplanar. These faces are placed in contact with the right angle flanges 22 and 23 formed integrally with the supports 20 and 21. These flanges may furthermore be provided with the upturned edges 24 and 25 adapted to engage the inner edges of the pole ends of the magnet 1.

The poles of magnet 1 are furthermore extended so as to provide an air gap 26 (Figs. 2 and 4) in which the flattened end 11 of the armature structure is accommodated. This gap is formed by the aid of the inwardly bent polar extensions 4 and 5, which may have their pole forming faces of reduced width, thereby restricting the areas of the poles. These polar extensions 4 and 5 are integral with side members 6 and 7. The members 7 and 20, and 6 and 21 may be appropriately attached for example, as by spot welding or the like. Thus the inwardly turned ends 17, 18 are in intimate magnetic contact with polar extensions 4 and 5 respectively.

The polar extension members 6 and 7 are provided with flanges 27 and 28 respectively. These flanges are intended to be disposed on top of

any appropriately formed bracket or support 29 extending across the bottom of the structure. In order to hold the magnet 1 securely in place, a long screw 30 may be provided, passing through the connecting portion of the magnet 1 and threaded into the support 29.

As thus far described, and as seen most clearly in Fig. 2, the armature structure is in the influence of the magnetism existing across the gap 26 between the restricted opposed areas of the pole pieces 4 and 5.

During the operation of recording, the armature structure is variably polarized by the aid of an electro-magnet coil such as 31, through which a current passes corresponding to the impulses to be recorded. The varying magnetism of the armature causes its flattened polar end 11 to vibrate in the air gap 26. Thus, if the polar extension 11 becomes the north pole, it will be attracted to the south pole of the air gap 26 and will be repulsed from the north pole. If the armature structure, on the other hand, is so influenced as to cause the polar extension 11 to be a south pole, the movement is in the reverse direction. For example, if pole piece 4 and extension 17 are north poles, and pole piece 5 and extension 18 are south poles, upon polar extension 11 becoming a north pole, it will be attracted toward pole piece 5, through the polar extension 11, to extension 17. Conversely, upon the polar extension 11 becoming a south pole, it will be attracted toward pole piece 4, and the magnetic path will be from pole piece 4, through the polar extension 11, to extension 18. The extent of the movement is made dependent upon the strength of the impulses; for example by placing a resilient restraint upon oscillations of the armature structure about its transverse axis. The strength of the impulses will then determine the amplitude of the armature oscillation. The manner in which these restraints are provided will be hereinafter described.

As the armature structure is thus oscillated by electrical impulses, the stylus 8 is also thus correspondingly oscillated about the transverse axis, and a record blank may be appropriately impressed by the stylus to form a laterally cut or indented record groove.

When the head is used for reproduction, the armature structure is mechanically vibrated or oscillated in the air gap by the contour of the record groove with which the stylus 8 is in contact. This oscillation causes the magnetic flux through the armature to vary as well as to change polarity as the armature pole 11 is swung from its neutral position toward one or the other pole face. These variations in magnetism are utilized to induce an electromotive force in the coil 31 disposed around the armature. This coil may thus serve for the dual purpose of influencing the armature structure for recording purposes; and of being influenced by the mechanical oscillation of the armature for reproducing purposes.

In the present instance the coil 31 is diagrammatically illustrated as disposed around the armature structure in the space formed between the pole pieces 4 and 5 and the inwardly turned extensions 17 and 18. Thus for example it may be supported on an insulation plate 32, as of fiber, fastened in any appropriate manner to the inner surfaces of the inwardly turned ends 17 and 18. This supporting insulation member 32 is appropriately apertured for the accommodation of the armature. The coil leads 33 and 34 are shown as being connected to the metallic terminal eyelets

35 and 36 supported on the insulation plate 37. This insulation plate may be appropriately fastened to the top surface of the bracket or support 29.

If the armature pole extension 11 is not perfectly centered in the air gap 26, it will be attracted to the nearer of the two poles, 4 and 5, resulting in unsatisfactory performance. Therefore, means must be provided to maintain the pole extension 11 centered in the air gap 26 except when force is applied to the armature. In recording, this force is due to magnetic polarity induced in the armature pole extension 11 by a pulsating current in the coil 31. In reproducing, this force is applied mechanically by the undulations in the record groove acting to deflect stylus 8.

In both cases, it is desirable to have an armature bearing which permits rotational movement of the armature structure about its axis, but which does not permit translatory movement of the armature structure at its axis.

The amount of such translatory motion, that is, a shifting of the armature axis in the direction of movement of the stylus, which occurs on account of the flowing of the rubber in the bearings, is nearly proportional to the amount of pressure applied in deflecting the armature. In reproducing, this pressure is light, and no special provision is required to prevent such translatory motion. In recording, however, this pressure is relatively heavy, due to the work done on the record material by the stylus, and considerable motion would be lost in the rubber journals.

To permit the use of rubber journals, with their advantages of low cost and freedom from looseness, means are provided to prevent translatory motion of the armature structure, which means also functions as a centering means.

For this purpose resilient struts are arranged above and below the armature structure and cooperate respectively with the extensions 12 and 13. These struts as shown most clearly in Figs. 1, 4, 5 and 6, may be in the form of the bar springs 38 and 39. These springs are attached as by soldering or welding, respectively to the extensions 13 and 12 and extend transversely to the axis of the extensions. They are anchored in clamps shown to best advantage in Figures 4, 5 and 6. Thus the support 21 is provided with inturned ears 40 and 41, at its upper and lower edges respectively, each ear having a forwardly extending bar 42, 43. Clamping bars 44 and 45 are respectively slidably supported on ears 40 and 41, each bar being provided with a slot 46 through which the fastening screw 47 may pass. Each clamping bar furthermore is provided with a groove near its extremity for the accommodation of the spring 38 or 39. By the aid of the adjustments provided for these spring clamps, the armature structure 9-11 may be readily placed in neutral position when the armature structure is uninfluenced. Thus, by adjusting each of the clamping bars 44 and 45 with respect to the respective screw 47, adjustment of the armature structure about its axis is effected. In this way the armature pole extension 11 may be readily centralized in the air gap 26.

The spring bars 38 and 39 are relatively easily deflected transversely, to permit sufficient movement of the armature about its axis. They are made just stiff enough in this sense to ensure centering. At the same time, these bars 38 and 39 have very great resistance to longitudinal compression or extension, and thus prevent motion of the armature axis in the direction of the long dimension of the bars. Since this long di-

5 mension is in the direction of movement of the stylus, the bars are effective to prevent translatory movement of the armature axis due to the movement of the stylus.

What is claimed is:

1. In a head for recording and reproducing impulses, a magnet structure having symmetrically spaced coplanar ends, supports respectively contacting the ends and extending transversely from the ends, said supports having opposed inwardly turned projections, a vibratory armature structure supported by the aid of said projections to oscillate on an axis transverse to the plane of the magnet ends, pole pieces for the magnet extending along the supports and having opposed spaced poles with which the armature cooperates, there being a space between the inwardly turned projections and the spaced pole piece ends, and an electromagnetic coil surrounding the armature and supported in said space by the inwardly turned projections.

2. In a device of the character described, for use in recording and reproducing impulses, an armature structure adapted to carry a stylus and having means forming a pole, as well as transverse extensions adapted to form journals on opposite sides of the structure, a magnet having poles between which the pole of the armature structure is disposed, bearing structures cooperating respectively with said extensions to support the armature structure for oscillation about a transverse axis, each of said bearing structures including a sleeve of resilient material encircling the extensions, and means whereby said armature structure axis is strongly restrained from displacement in a direction such as would disturb the centering of the pole of the armature between the magnet poles, and whereby said armature structure axis is resiliently restrained from displacement in a direction corresponding to the axis of the armature when the armature is central between said magnet poles, said means comprising a pair of bar springs secured respectively to said extensions and extending in the direction of the desired strong restraint.

3. In a stylus head for use in recording and reproducing impulses, an armature structure adapted to carry a stylus and having means forming a pole as well as transverse extensions on opposite sides of the structure, a magnet having poles between which the armature pole is disposed, bearing structures cooperating respectively with said extensions to resiliently support the armature structure for oscillation about a transverse axis, and means resiliently opposing said oscillation comprising a pair of bar springs secured respectively to said extensions and extending in the direction of the oscillatory movement whereby the said axis is prevented from moving in said direction.

4. In a stylus head for use in recording and reproducing impulses, an armature structure adapted to carry a stylus and having means forming a pole as well as transverse extensions on opposite sides of the structure, a magnet having poles between which the armature pole is disposed, bearing structures cooperating respectively with said extensions to resiliently support the armature structure for oscillation about a transverse axis, said extensions having ends projecting beyond said bearing structures, and a pair of bar springs secured respectively to said ends and extending transversely to said extensions, said springs resiliently opposing said oscillation.

and preventing translatory movement of the armature structure in the direction of the oscillations.

5. In a stylus head for recording and reproducing impulses, an armature structure adapted to carry a stylus and having means forming a pole as well as transverse extensions adapted to form journals on opposite sides of the structure, a magnet having poles between which the armature pole is disposed, bearing structures cooperating respectively with said extensions to support the armature structure for oscillation about a transverse axis, each of said bearing structures

including a sleeve of resilient material encircling the corresponding extension and means opposing translatory movement of said axis in the direction of the oscillations, comprising a pair of bar springs respectively secured to said extensions and extending in the direction of the oscillatory movement of the stylus, and anchoring means for each of said springs, said means permitting adjustment of the spring in the direction of said movement, whereby the armature pole may be centered between the magnet poles.

BERNARD F. McNAMEE.
